CLAIM

The ornamental design for a starter pier for a pier bracket assembly, as shown and described.

DESCRIPTION

FIG. 1 is a perspective view of the starter pier for pier bracket assembly;

FIG. 2 is a leading end view of FIG. 1;

FIG. 3 is a rear end view of FIG. 1;

FIG. 4 is a first side view of FIG. 1;

FIG. 5 is a second side view of FIG. 1;

FIG. 6 is a third side view of FIG. 1;

FIG. 7 is a fourth side view of FIG. 1; and,

FIG. 8 is a side view of the starter pier of FIG. 1, shown in condition of use.

The claim is shown with a symbolic break in its length. The appearance of any portion of the article between the break lines forms not part of the claimed design.

The broken lines in the drawings depict portions of the starter pier for pier bracket assembly that form no part of the claimed design. The broken lines showing the pier bracket assembly in FIG. 8 depicts environment that forms no part of the claimed design.

The surface shading, if any, illustrated in the figures is provided merely to highlight the contour of the design and it is not intended to be illustrative of texture or gloss.
